(57) **CLAIM**

The ornamental design for a tilted loader/receiver, as shown and described.

DESCRIPTION

FIG. 1 is a side view of a cylindrical-shaped tilted loader/receiver in accordance with our new design.

FIG. 2 is a front view of the cylindrical-shaped tilted loader/receiver shown in FIG. 1.

FIG. 3 is an opposing side view of the cylindrical-shaped tilted loader/receiver shown in FIG. 1.

FIG. 4 is a back view of the cylindrical-shaped tilted loader/receiver shown in FIG. 1.

FIG. 5 is a top view of the cylindrical-shaped tilted loader/receiver shown in FIG. 1.

FIG. 6 is a bottom view of the cylindrical-shaped tilted loader/receiver shown in FIG. 1; and,

FIG. 7 is a front view illustrating the environment, showing a conical-shaped loader/receiver and a cylindrical-shaped loader/receiver mounted on hoppers, tilted at angles.

The characteristic feature of the design resides in a loader/receiver being tilted at an angle rather than being positioned vertically.

The broken line showing is for illustrative purposes only and forms no part of the claimed design.
